UNITED STATES PATENT OFFICE.

HUGO BORCHARDT, OF BERLIN, GERMANY.

BREECH MECHANISM FOR SMALL-ARMS.

No. 918,951.

Specification of Letters Patent. Patented April 20, 1909.

Application filed July 30, 1907. Serial No. 386,210.

To all whom it may concern:

Be it known that I, HUGO BORCHARDT, engineer, a citizen of the United States of America, residing at No. 31 Kantstrasse, Berlin-5 Charlottenburg, in the Kingdom of Prussia, Germany, have invented certain new and useful Improvements in or Connected with Breech Mechanism for Small-Arms, of which the following is a full, clear, and exact de-10 scription.

The present invention refers to a toggle joint breech mechanism for automatic fire arms with fixed barrels, and the object of the invention is, to obtain a new mechanical 15 method for breaking the toggle joint. For this purpose a swinging counter support, pivoted to the end journal of the toggle joint is interposed and placed at such an angle as to make it give away in the opening direction 20 when pressure is brought to act upon the toggles.

According to the form of construction shown in Figures 1 and 2 the counter support (bearing) *c* is provided with an arm, which 25 serves as a carrier for the link *b* of the toggle joint *a b*, which is pivoted thereto. The swinging motion of the counter support *c* is limited by stops and imparts a short initial breaking movement to the toggle joint. 30 Even though the movement of the counter support *c* resulting from the gas pressure upon the base of the cartridge case breech-block and toggle joint is but slight, it nevertheless imparts sufficient kinetic energy to 35 the toggle joint to fully open the breech mechanism and place a spring under tension, which acting upon the toggle joint again closes the breech. The counter support can be arranged to act either upon the front or 40 upon the rear link of the toggle joint.

Figs. 3 and 4 show a construction in which the breech block *k* by having a slight vertical play at *k'* is made to answer as movable counter support to the forward link. Applying this arrangement the head of the cartridge case becomes slightly deformed, which however does not occasion any obstruction or inconvenience. 45

What I claim as my invention, and desire to secure by Patent is:

1. In a fire arm, a breech mechanism having a toggle joint and means for giving such toggle joint a small initial breaking movement when the cartridge is fired, whereby such toggle is thrown out of its locking position and is enabled to easily fold, said means comprising a movable counter support pivoted to one of the members of the toggle and adapted to throw such toggle away from the locking position when the breech block is 50 pressed backwardly. 55

2. In a fire arm, a breech mechanism having a toggle joint and means for giving such toggle joint a small initial breaking movement when the cartridge is fired, whereby such toggle is thrown out of its locking position and is enabled to easily fold, said means comprising a breech block pivoted to one of the members of said toggle, said breech block having a slight vertical play, whereby 65 it is tilted to a slight extent so that it throws said toggle away from the locking position. 70

In witness whereof, I have hereunto signed my name in the presence of two subscribing witnesses.

HUGO BORCHARDT.
